UNITED STATES PATENT OFFICE.

GEORGE L. ZUCKER, OF EAST ORANGE, NEW JERSEY.

FUEL ECONOMIZER.

Application filed March 28, 1925. Serial No. 19,185.

My invention relates to an improvement in fuel economizers.

It is a recognized fact that a very large percentage of the heat of stoves and furnaces passes up through the chimney and is lost. Also quite a large percentage of fire loss results from flue fires. In heavy winds gas in houses results from the back draft due to high winds.

10 The object of my invention is to conserve and utilize the heat units, to prevent flue fires, and back drafts through chimneys.

This invention consists in a metal cone adjustable as to size to fit different size 15 smoke pipes or flues of various sizes. It further consists in means for catching and preventing the passage of escaping embers that are frequently drawn up through the smoke-pipe where the lighter fuels are burned, such 20 as wood, corncobs, paper and the like.

In the accompanying drawings:—

Fig. 1 is a section through a smoke-pipe, the full lines showing a large size pipe, and the dotted lines a smaller size with my improved device centered therein; and

Fig. 2 is a view taken at right-angles to Fig. 1 looking in the direction of the arrow.

The numeral 1 represents a cone of sheet-metal having a central outlet or nozzle 2, and provided with orifices 3 in the sides. This cone is divided at its larger end by slits 4 into a plurality of wings or fins 5 which are adapted to be bent or spread to fit the inner wall of the smoke-pipe 6, as shown in 30 the drawings. In the full lines shown in Fig. 1, these fins or wings are bent out to the utmost to the largest size pipe 6 that this particular device is made to fit, whereas the dotted lines show the fins or wings approximately in alignment with the body of the cone to fit a smaller size pipe. The slits or 40 slots 4 are of sufficient width, however, to admit of these fins or wings being bent inwardly to the size of the main portion of the cone as indicated by the dotted lines at 45 7, so that the device might be used in a smoke pipe of the diameter of the widest part of the cone proper, as indicated at X.

At the inner ends of the slits or slots, enlargements 8 are formed as clearly illustrated in Fig. 2. These prevent the metal from breaking or splitting at these points and form vents along with the orifices 2 and 3 for the passage and escape of the products 50 of combustion.

As a means of bracing the smaller end of

the cone, two brace rods or wires 9 are employed, they extending through holes 10 in the cone at right-angles to each other. The outer ends may be bent to engage the inner 60 wall of the pipe as shown in Fig. 1. These braces might be inserted forward through the holes 11, if desired.

As a means of preventing the passage of light flying embers, the reticulated screen 65 12 is employed. This may be variously constructed, but is adapted to be bent into concavo-convex shape as shown in Fig. 1, and it is preferably held together by reinforcing wires 13 having hooks 14 at the ends by 70 which they are fastened to the screen 12. A main brace 15 supports the back of this screen through the center, and a wire 16 passed through holes in the cone and between the center brace and screen holds it 75 in the cone.

The reticulated screen is so constructed that it is easily adjusted to the size or diameter of the pipe or chimney, it being made of a size of wire that renders it easily bendable, and the reinforcing wires 13 are adapted to hold, brace and reinforce the screen in its adjusted position. A simple means of varying the size and the cavity of the screen would be to slit the flat blank of reticulated 80 material in toward the center at intervals and overlap the slit portion the required amount, to adjust the screen to the size of the pipe or chimney, and when thus adjusted to hold or fasten it by means of the reinforcing wires hooked into the reticulated material.

In fitting my improved fuel economizer to a smoke-pipe or chimney, the wings or fins 5 are progressively spread apart or bent 85 outwardly to engage frictionally the smoke-pipe or chimney, thus producing vent spaces of graduated size from plus normal or approximately as illustrated in Fig. 1 to capacity of the wings or fins as shown in full 90 lines in Fig. 1. In other words, the larger the smoke-pipe or chimney, the more the wings or fins are distorted and bent away from the original position at normal, and as larger size smoke-pipes or chimneys require more vent or draft, the progressive widening or graduation of vent spaces provides this requirement. It is understood that the reticulated screen is likewise adjustable to correspond approximately to the 100 diameter of the pipe or chimney, and to fit the same, and that the wings or fins and

reticulated screen are intended to co-operate with each other, size for size.

By the use of this device, a very simple contrivance is provided for use in any pipe or chimney. It does not stop the necessary draft through the pipe or chimney, but it does retard the products of combustion, and allows them to be consumed within the stove or furnace, so that the large percentage of the heat units may be utilized rather than wasted.

At the same time it stops the passage of flying embers, it prevents excessive heat in the flue, it stops back-draft, and thus prevents the gas of the fire pot being blown into the room or place where the stove or furnace is located.

The device is easily and quickly applied, and generally holds its position by frictional engagement in the pipe. If the device is to be applied in an unusual location or position, any suitable supporting means can be employed; however, under ordinary conditions of application this is not necessary.

The entire article is not only simple but inexpensive, but most efficient in the accomplishment of its purposes.

I claim:

1. In a device of the character described, 30 the combination of a cone having vents

therein, and means for adjusting it to the size of a pipe or chimney, and a reticulated screen removably attached at the enlarged end of the cone.

2. A device of the character described, 35 the combination of a cone having vents therein, means for adjusting it to the size of a pipe or chimney, a reticulated screen removably attached at the enlarged end of the cone, braces, reinforcing wires for supporting and holding the reticulated screen 40 in shape and a removable wire for fastening the screen to the cone.

3. A device of the character described including a perforated cone having its larger 45 end slotted longitudinally, and adapted to be expanded radially for fitting the cone and fastening it frictionally to various sizes of pipes.

4. A device of the character described including a perforated cone having its larger 50 end slotted longitudinally, and adapted to be expanded radially for fitting the cone and fastening it frictionally to various sizes of pipes and braces connected with the smaller 55 end of the cone and extending to the inner walls of the pipe or chimney.

In testimony whereof I affix my signature.

GEORGE L. ZUCKER.
